UNITED STATES PATENT OFFICE

FREDERICK BOXLEY, OF OAKLAND, CALIFORNIA

ACOUSTIC DEVICE

Application filed September 9, 1926. Serial No. 134,358.

This invention relates to acoustic devices for sound reproducers and especially to diaphragms capable of reproducing and amplifying sound vibrations of a phonograph record or the high frequency vibration of a telephone receiver, a radio loud speaker unit or the like.

The object of the present invention is to generally improve and simplify the construction and operation of sound reproducing diaphragms; to provide a sound reproducing diaphragm of the cone-shaped type in which the diaphragm may be materially decreased and the total area presented materially increased and further to provide a novel mounting which leaves the peripheral edge of the diaphragm entirely free and unsupported so that the vibrations transmitted to the diaphragm will bodily move the same throughout its entire area.

One form which the invention may assume is shown by way of illustration in the accompanying drawings, in which:

Figure 1 is a central vertical longitudinal section of a loud speaker cabinet showing a loud speaker unit mounted therein and also the diaphragm forming the subject matter of the present application.

Figure 2 shows a modified form of diaphragm.

Referring to the drawings in detail and particularly to Figure 1, A indicates a sounding board of suitable construction, B a loud speaker unit and C the diaphragm. The diaphragm together with the vibrating unit actuating the same is, in this instance, enclosed within a cabinet in which 4 indicates the base, 3 the front grill through which the sound waves are emitted and 2 the top, the sounding board being suitably secured between the base and the top section, as will be readily understood. The diaphragm proper forming the subject matter of the present application is, broadly speaking, cup-shaped. It is supported by a rod 9 which, in turn, is attached to the vibrating arm 8 of the speaker unit B, while the opposite end is suitably supported in a bearing member 10, as will hereinafter be described.

Any suitable vibratory type of unit may be

employed but in the present instance, a balanced armature type is illustrated, in which 5 indicates the armature, 6 the pivot about which it vibrates and 7 a link connection between the armature and the vibrating arm 8. 55 The function of vibratory units of this character is well understood and a detailed description of the circuits actuating the same is thought unnecessary. Sufficeth to say that when the unit is connected with a radio set, 60 current pulsations of high frequency are set up in the unit and the armature is thereby swung about its pivot 6, the movement of the armature being transmitted through the connection 7 to the vibrating arm 8 and rod 9 65 which is, accordingly, reciprocated or vibrated on the line of its longitudinal axis and as the diaphragm C is directly attached thereto, the entire diaphragm will be bodily moved throughout its entire area. 70

The diaphragm, in turn, reacts with the sounding board A and the audible sound waves are projected through the grill 3 in the usual manner. The construction of the diaphragm and mounting thereof is exceedingly important. It consists of two sections generally indicated at 11 and 12, the member 11 being cone-shaped and the member 12 a frusto-conical shell. The cone is inverted with relation to the frusto-conical shell that is the apex of the cone is pointed in the direction of the largest diameter of the shell. The periphery of the cone is flanged as indicated at 14 and is glued or otherwise secured to the small end of the shell. One end of the shell is, in this manner closed and a diaphragm of large area and small diameter is obtained which reacts with the sounding board A to produce the audible sound waves. 80 In actual practise, I have found that the diaphragm as a whole should be left free and unobstructed as far as possible, as the clearest reproduction or sound transformation is thereby obtained. In this instance, the rod 9 extends through the apex of the cone 11 and is rigidly secured thereto in any suitable manner, for instance, by furks 15 and the screws 16. This manner of securing the diaphragm with relation to the vibrating rod 9 leaves the peripheral edge of the cone and 85 90 95 100

- the shell 12 entirely free and unsupported and the entire diaphragm is, accordingly, moved throughout its entire area when the vibrations are transmitted through the rod. 5 To further insure free transmission of the vibrations a flexible support for the outer end of the rod 9 is desired. In the present instance, a bracket 17 is employed and a rubber bearing or sleeve 18 is placed in the upper end thereof. The outer end of the rod 9 rests in the rubber bearing and resistance to vibratory movement is thereby reduced to a minimum. 10
- The cone 11 and shell 12 may be constructed of paper, celluloid, metal and other suitable materials and in actual practise parchment, paper or the like has been successfully employed. The exact thickness of the paper is not important as it is found that the deeper tones are best reproduced when the diaphragm is fairly heavy and that the high-pitched tones are best reproduced with a lighter cone, and for this reason two cones are illustrated, the one at C and the second 20 at D.
- Where two are employed one diaphragm will be constructed of a heavier material and the other of a lighter material and substantial perfect reproduction is obtained, as one 25 diaphragm will take care of higher pitched tones and the second will take care of the lower tones. The diaphragms may be pointed in the same direction or they may be reversed with relation to each other, as 30 desired. For instance, the rod 9 might be extended through the arm 8 and the speaker unit and the sounding board A. The second diaphragm could thus be placed on the opposite side of the sounding board. 35
- 40 Numerous modifications of this character can of course, be resorted to and any detailed description thereof is thought unnecessary. In Figure 2 a modified form of the diaphragm is illustrated. In that instance corrugations are formed in the cone 11, as indicated at 19. When the cone is constructed in this manner, part of the vibrations are absorbed in the cone and the remaining vibrations are transmitted to the shell. Excellent tone reproductions are obtained in either case.
- While certain features of the present invention are more or less specifically described, I wish it understood that various changes 55 may be resorted to within the scope of the appended claims. Similarly that various materials and finishes of the several parts employed may be such as the manufacturer may decide or varying conditions or uses may demand.
- Having thus described my invention, what I claim and desire to secure by Letters Patent is:—
1. An acoustic device comprising a rod 60 connected at one end with a vibratory sound
- reproducer, a support for the opposite end of the rod and a diaphragm secured to the rod at a point intermediate the ends thereof, said diaphragm having its peripheral edge entirely free and unsupported so that vibrations transmitted to the rod will bodily move the diaphragm throughout its entire area. 70
2. An acoustic device comprising a rod connected at one end with a vibratory sound reproducer, a flexible support for the opposite end of the rod and a diaphragm secured to the rod at its central point and intermediate the ends of the rod, said diaphragm having its peripheral edge entirely free and unsupported so that vibrations transmitted to the rod will bodily move the diaphragm throughout its entire area. 75
3. An acoustic device of the character described, a diaphragm comprising a frusto-conical shaped shell open at one end, and a cone-shaped diaphragm forming a closure for the smaller open end of the shell. 80
4. In an acoustic device of the character described, a diaphragm comprising a frusto-conical shaped shell, and a conical diaphragm secured in the small end thereof, the apex of the cone pointing in the direction of the larger end of the shell. 85
5. In an acoustic device of the character described, a diaphragm comprising a frusto-conical shaped shell, a conical diaphragm secured in the small end thereof, the apex of the cone pointing in the direction of the larger end of the shell, a rod in the longitudinal axis of the shell, and the cone and 90 connected at one end with a vibrating sound reproducer, and means whereby the rod is secured to the apex of the cone. 95
6. An acoustic device comprising a rod connected at one end with a vibrating sound reproducer, and a cup-shaped diaphragm secured to the rod and bodily movable with the rod. 100
7. An acoustic device comprising a rod connected at one end with a vibrating sound reproducer, a cup-shaped diaphragm secured to the rod and bodily movable with the rod, and a sounding board co-operating with the open end of the diaphragm. 110
8. An acoustic device comprising a rod connected at one end with a vibratory sound reproducer and a cup-shaped diaphragm secured to the rod and bodily movable with the rod, the side of the cup-shaped diaphragm flaring from top to bottom like a cone with 120 the largest diameter at the top or open end. 115
9. An acoustic device of the character described comprising a frusto-conical shaped shell open at one end, a cone-shaped diaphragm forming a closure for the smaller 125 end of the shell, and corrugations formed in a portion of the surface of the cone-shaped diaphragm.
